SNOW PLOW

Herman E. Bahr, Doylestown, Wis.

Application January 14, 1937, Serial No. 120,601

5 Claims. (Cl. 37—49)

This invention relates to a snow plow and it aims to provide a novel construction adapted to be pushed by a tractor or other source of power and to remove the snow with the expenditure of less power than heretofore.

It is particularly aimed to provide such a construction wherein the snow is elevated in strips and while elevated is discharged, to effect the removal with minimum power.

10 It is also aimed to provide such a structure as is capable of maximum adjustment and has moldboards adapted to discharge to either side or to discharge solely to one side as preferred.

15 Various additional objects and advantages will become apparent from a consideration of the description following taken in connection with accompanying drawings illustrating an operative embodiment.

In said drawings:—

20 Figure 1 is a side elevation of my improvements shown attached to a tractor;

Figure 2 is a plan view of the parts of Figure 1;

Figure 3 is a detail section taken on the line 3—3 of Figure 2;

25 Figure 4 is a detail section taken on the line 4—4 of Figure 1;

Figure 5 is a fragmentary end elevation of the forward portion of the device; and

Figure 6 is a detail section taken on the line 30 6—6 of Figure 2, being on an enlarged scale.

Referring specifically to the drawings wherein like reference characters designate like or similar parts, the device comprises parallel longitudinal beams 10 preferably of metal adapted to be fastened removably by bolts or the like as at 11 to a tractor 12 which is representative of any source of power which may be used to push the improvements. The beams 10 adjacent their forward ends are supported by skids or runners 13 preferably connected to the beams by hydraulic lift or jack mechanism 14. In order that the beams and skids will follow the surface from which the snow is being cleaned, the beams are preferably in articulate sections hinged together as at 15.

45 A flat or sheet-like plow blade is provided at 16, preferably of metal and of any desired size, the same being hinged or pivotally connected on a horizontal axis as at 17 to the forward ends of the beams 10. The forward end of the blade 16 may be reenforced with a scraper 18 whose forward edge is preferably sharpened as shown, the scraper being riveted or removably bolted as at 19 to the plow blade.

50 Adjacent the rear of the beams 10, sections 20 of hydraulic jacks are attached thereto and other

sections 21 of such jacks are in contact with the lower surface of the blade 16 so that the jacks 20—21 may be operated to raise or lower the blade 16 at the rear thereof, the parts 21 sliding along the undersurface of the blade, incidental to such adjustment.

A moldboard co-acts with the blade 16 and is made in similar sections 22, having wings 23 thereon beyond the blade. Such moldboard sections may be used in V-formation as shown in full lines in Figure 2 or may be used in a single line depending on whether the snow is to be thrown to both sides of the blade or to one side only. At the inner ends of the moldboards they are connected together by a hinge 24 to a leaf of which a depending stud 25 is fastened or cast integral, and which stud travels longitudinally in a slot 26 disposed centrally and longitudinally of the plow blade 16. Laterally extending trunnions 27 are provided on stud 25 and rollers 28 are journaled thereon and ride on the blade 16 on opposite sides of the slot 26. Below the blade 16, trunnions 29 extend laterally from the stud 25 and have rollers 30 journaled thereon which engage the undersurface of the blade 16. In this manner, a carriage is provided which will enable movement of the inner end portions of the moldboards with minimum friction. In order to fasten the inner ends of the moldboards rigidly to the blade 16, a lug 31 extends from the stud 25, having a set screw 32 threaded therein and adapted for binding against the undersurface of the blade 16. Because of the hinge connection at 24 and the fact that the carriage is longitudinally adjustable, the moldboards 22 may be arranged at any desired location either in V-formation or in parallelism to divert the snow to either side of the board 16 as preferred.

55 Guides and clamps 33 are riveted or otherwise fastened as at 34, one to each moldboard 22 and they have bifurcations 35 interengaged with guide rods 36 disposed below, in parallelism to and fastened at their ends to the blade 16. The bifurcations of the clamps 33 enable them to engage or disengage the adjacent rods 36 and such clamps have ears 37 in which set screws 38 or the equivalent are screw threaded and adapted to bind against the rods 36 to rigidly hold the moldboards in the desired positions.

Integral or rigid with the scraper 18 are vertical 60 parting strips 39, one located centrally of the blade 16 and one adjacent each side thereof and each being braced as by means of a bar 40 riveted thereto as at 41 and riveted to the blade 16 as at 42.

As a result of the construction described, the plow member or blade 16 may be disposed at any desired angle with its scraper 18 at any suitable elevation above the ground or surface to be cleared. The source of power 12 will push the apparatus with the scraper 18 foremost and the snow will ride upwardly along the blade 16, severed into two strips because of the presence of the parting strips 39. Such strips of snow will come into contact with the moldboards 22 and be forced off of the blade 16, at an elevation higher than the undisturbed snow, with the latter offering no resistance, it being understood that the moldboards 22 may be arranged in the V-formation so as to discharge on both sides of the blade 16 or they may be arranged in alignment to throw or cast the snow entirely to either side of the blade, the moldboards being readily adjustable as described. When the snow rides upwardly on the blade 16, it may be turned from the same without much power and without compacting snow in advance of the implement. In the case of snow which is soft and dry, and resistance is not apt to be encountered by pushing the implement forwardly into the same, the blade 16 is lowered as nearly as practical to the horizontal.

Various changes may be resorted to provided they fall within the spirit and scope of the invention.

30. I claim as my invention:—

35 1. Apparatus of the class described comprising a plow blade, moldboard sections thereon, said blade having a longitudinal slot, a stud disposed in said slot, means carried by the stud overlapping the upper and lower surfaces of the plow blade, means on the stud hinging the adjacent ends of the moldboard sections together, and means to secure the moldboard sections in adjusted positions.

10. 2. Apparatus of the class described comprising a plow blade, moldboard sections thereon, said blade having a longitudinal slot, a stud disposed in said slot, means carried by the stud overlapping the upper and lower surfaces of the plow blade,

45 means on the stud hinging the adjacent ends of

the moldboard sections together, and means carried by the stud adapted for binding engagement against the blade.

3. Apparatus of the class described comprising a plow blade, moldboard sections thereon, said blade having a longitudinal slot, a stud disposed in said slot, means carried by the stud overlapping the upper and lower surfaces of the plow blade, means on the stud hinging the adjacent ends of the moldboard sections together, means carried by the stud adapted for binding engagement against the blade, and clamp means carried by each moldboard section to secure the same in adjusted positions to the plow blade.

adjusted positions to the plow blade.

4. Apparatus of the class described comprising a plow blade, moldboard sections thereon, said blade having a longitudinal slot, a stud disposed in said slot, means carried by the stud overlapping the upper and lower surfaces of the plow blade, means on the stud hinging the adjacent ends of the moldboard sections together, means carried by the stud adapted for binding engagement against the blade, a clamp carried by each moldboard section, longitudinally extending rods below and connected to the plow blade, said clamps having bifurcated portions engaging said rods, and binding means on said clamps engageable with said rods.

5. Apparatus of the class described comprising a plow blade, moldboard sections thereon, said blade having a longitudinal slot, a stud disposed in said slot, means carried by the stud overlapping the upper and lower surfaces of the plow blade, means on the stud hinging the adjacent ends of the moldboard sections together, means carried by the stud adapted for binding engagement against the blade, a clamp carried by each moldboard section, longitudinally extending rods below and connected to the plow blade, said clamps having bifurcated portions engaging said rods, binding means on said clamps engageable with said rods, parting strips rising from the plow blade at the forward end thereof, and means to adjustably mount the plow blade and connect it to a pushing vehicle. 30 35 40
